UNITED STATES PATENT OFFICE.

WINFIELD H. STANNARD, OF MATTESON, ILLINOIS, ASSIGNOR TO CENTRAL SCIENTIFIC COMPANY, OF CHICAGO, ILLINOIS, A CORPORATION OF ILLINOIS.

CONSTANT-TEMPERATURE OVEN.

Application filed November 30, 1925. Serial No. 72,208.

This invention relates to ovens for administering treatment at constant temperatures and has for its principal objects to provide a greater uniformity of temperature throughout the different parts of the oven and a greater time-constancy of temperature of the oven as a whole. More specific objects will appear and be best understood as the disclosure proceeds and the description is read in connection with the accompanying drawings illustrating the preferred embodiment of the invention, in which

Fig. 1 is a vertical section through the oven;

Fig. 2 is a transverse section thereof;

Fig. 3 is a perspective view of a unit including the preferred electrical equipment for the oven;

Fig. 4 is a plan view of the panel arrangement, and

Fig. 5 is a wiring diagram illustrating the most advantageous connection of the apparatus.

The most satisfactory oven enclosure for general application includes a bottom 10 and a top 11 connected by sides 12 and 13, a back 14 and a front 15. Each of these is so fabricated of suitable materials as to be as nearly non-conducting as practicable. For example, each part of the enclosure may consist of an outer sheet of asbestos board 16, spaced from an inner sheet of like board 17, by a filling of asbestos fiber, mineral wool, or the like 18.

The front 15 is shown as a door, hinged at 19, and having beveled edges 20 to make a close joint with corresponding edges 21 on the facings 22 attached to the sides 12 and 13.

For the best results the electric heating element should consist of a plurality of units presenting uniform wattage throughout their length. For example, the units may be coils 23 extending around the lower portion of the container and supported in notched blocks 24 of asbestos board 24, secured to a base 25 of asbestos board, or other material, that will not reflect or radiate heat to a great extent.

Extending upwardly from the heating element is a flue, or flues, 26, in open communication with the enclosure at both ends. In the simple construction shown, a wall 27 extends across the enclosure spaced a short distance from the back 14 and terminating just above the blocks 24 at the bottom 10, and about the same distance from the top 11.

Secured to this wall and extending parallel to the sides of the corresponding facings, are walls 28 and 29, which terminate short of the door 15 and are supported by brackets 30. A wall 31, of glass, normally rests against the front edges of the walls 28 and 29, and is supported by springs 32 on a door frame 33, which is fitted with a second glass wall 34 in spaced relation to the wall 31. The door frame 33 is hinged to one facing 34 and closes against an opposed facing 35 secured respectively to the sides 12 and 13. The springs 32 serve to hold the glass wall 31 in proper relation and permit it to make slight adjustments in opening and closing the inner door. The walls 28 and 29 are equipped with supports for shelves 36.

The side 13 is cut away adjacent to the bottom to form an elongated opening 37 through which the base 25 with the heating element thereon, may be slid in inserting that element into or withdrawing it from the container. Attached to the base 25 is a block 38 of insulating material, such as transite, and to this, in turn, is attached a panel 39, adapted to carry various instruments and the wiring. The outer casing of the wall 13 is made in two pieces overlapped, as indicated at 40 to provide space 41 inwardly with respect to the panel, for the connections to the various instruments. This wall is also perforated at 42 to admit the thermoregulator 43, which is preferably of the type set forth in the patent to de Khotinsky, No. 1,375,780 of April 26, 1921.

In addition to the thermoregulator, the panel carries a connecting plug 44, a switch 45, a pilot lamp 46 and condensers 47.

Referring to the wiring diagram in Fig. 5, it will be seen that the coils 23 are arranged as separate units connected in parallel across the line 48.

The best results are obtained when these units are all the same wattage and two of the units are controlled by the thermoregulator through separate contacts 49 and 50.

The bottom 10 is provided with inlet passages 51 and the top with a vent 52.

Operation: When current is supplied to the heating element, air directly in contact with the coils becomes heated and rises. In its upward movement it entrains, or otherwise carries along other air. Thus convection currents are established which pass upwardly through the flues then inwardly and

downwardly through the enclosure between the flue walls, and outwardly through and around the coils and upwardly again through the flues. During the upward movement the highly heated air and the air carried with it become mixed until the product at the top of the flues is practically uniform in temperature. This flows inwardly and downwardly over the material to be treated and thus establishes throughout the space between the flue walls a zone of practically uniform temperature.

Placing the walls 27, 28, 29 and 31, inwardly with respect to the coils, not only insures that the heated air will immediately pass into the flues, but results in shielding the test material near the top of the oven from heat radiated directly from the coils while allowing such radiated heat to reach the test material near the bottom; thus the radiated heat reaches only that material that, were it heated by convection currents only, would be cooler than material near the top. Thus, the two sources of heat are so balanced that material near the top of the oven is at the same temperature as material near the bottom.

The glass walls 31 and 34 in the inner door permit inspection of the material on the shelves without opening the oven to drafts.

The heating element with its base and panel 39 form a detachable unit that is readily mounted and dismounted permitting quick access to all electrical equipment.

By making the regulated portion of the heating element substantially equal to two of the unregulated units the danger from changes in room temperature is practically eliminated. Suppose the room temperature to be 71° F. at the beginning of the treatment, the desired temperature in the oven 100° F., the wattage in the two units 23 sufficient to raise the temperature 20°. If only a single unit 23 was under the control of the thermoregulator and the room temperature dropped 3° there would be a failure of regulation. However, by having the regulated portions of the heating element of substantially the same wattage as two units 23 it is always possible to prevent either a drop or an increase in room temperature from taking the desired temperature out of the range of control of the regulator.

By breaking the regulated portion into a plurality of units the damage to the contacts is greatly reduced.

The pilot lamp 46 connected as shown in Fig. 5, will be lighted when the regulated units are in operation and will be dark when the regulated units are cut out. To reduce the current through the lamp it may be connected across a suitable shunt 53.

I claim as my invention:

1. In a device of the class described, the combination of an oven enclosure, including

a bottom, a top and walls, a heating element extending about the enclosure and located adjacent to the bottom, and the walls, and a flue communicating at its bottom with the heating element and extending upwardly along the walls and delivering adjacent to the top.

2. In a device of the class described, the combination of an oven enclosure including a bottom, a top and walls connecting the bottom and top, inner walls spaced inwardly from the walls of the enclosure and forming with the first wall a flue surrounding the oven space, said inner walls being cut away adjacent to the bottom and top, and a heating element adjacent to the bottom of the space between the outer and inner walls, said flue communicating at its bottom with the heating element, and at its top with the oven space.

3. In a device of the class described, the combination of an oven enclosure including a bottom and a top connected by side walls, an electric heating element of uniform wattage arranged around the oven adjacent to the bottom and the walls, and flue walls extending upwardly inside of the heating element and defining with the side walls upright flues having open bottoms in communication with the heating elements.

4. In a device of the class described, the combination of an oven enclosure including a bottom and top connected by walls having a door, flue walls spaced inwardly from the walls of the enclosure and including a transparent door opposite to the first door.

5. In a device of the class described, the combination of an oven enclosure including a bottom and a top connected by front, back and side walls, one of said walls having a door permitting access to the enclosure, a flue within the enclosure including a transparent door opposite to the door in the wall of the enclosure.

6. In a device of the class described, the combination of an oven enclosure including a bottom and a top connected by front, back and side walls one of said walls including a door and a flue connecting the lower and upper portions of the enclosure adjacent to each of said walls.

7. In a device of the class described, the combination of an oven enclosure including a bottom and a top connected by front, back and side walls, one of said walls having a door, a flue within the enclosure including a plurality of transparent walls movable to and from a position behind said door.

8. In a device of the class described, the combination of an oven enclosure including a bottom and a top connected by walls, one of which has an opening adjacent to the bottom, a base movable through said opening into and out of the enclosure and an electrical resistance element carried by the base

and movable therewith through the opening.

9. In a device of the class described, the combination of an oven enclosure including a bottom and a top connected by walls, one of which has an opening adjacent to the bottom, an electrical resistance element, a base for said element movable through said opening into and out of the enclosure, and an instrument panel attached to the base and adapted to close said opening when the base is within the enclosure.

10. In a device of the class described, an electrical heating element including several units, a plurality of which are of substantially equal wattage and a thermo-regulator controlling a portion only of said units substantially equal in wattage to two of the units of equal wattage, the remaining heating units being permanently in circuit.

11. In a device of the class described, an electrical heating element, including a plurality of units of substantially equal wattage, and thermo-regulating means controlling two of said units only, the remaining heating units being permanently in circuit.

25

12. In a device of the class described, the combination of an oven enclosure including a bottom, a top and walls connecting the bottom and top, inner walls spaced inwardly from the walls of the enclosure and cut away adjacent to the bottom and top, and a heating element looped about the bottom of the enclosure between the inner and outer walls.

13. In a device of the class described, the combination of an oven enclosure including a bottom, a top and walls connecting the bottom and top, inner walls spaced inwardly from the walls of the enclosure and cut away adjacent to the bottom, the inner and enclosure walls defining flues having open bottoms, one of the enclosure walls having an opening adjacent to the bottom, and an electrical resistance element extending about the bottom of the oven adjacent to the bottom of the inner walls and being removable through said opening, said resistance being in communication with the open bottoms of the flues.

In testimony whereof I affix my signature.

WINFIELD H. STANNARD.
